T. W. FOSTER

VANITY CASE

Filed April 4, 1925

Theodore W. Foster Inventor
By Joseph A. Miller

Attorney

UNITED STATES PATENT OFFICE.

THEODORE W. FOSTER, OF PROVIDENCE, RHODE ISLAND, ASSIGNOR TO THEODORE W. FOSTER & BRO. COMPANY, OF PROVIDENCE, RHODE ISLAND.

VANITY CASE.

Application filed April 4, 1925. Serial No. 20,669.

To all whom it may concern:

Be it known that I, THEODORE W. FOSTER, a citizen of the United States, residing at Providence, in the county of Providence and State of Rhode Island, have invented new and useful Improvements in Vanity Cases, of which the following is a specification.

This invention relates to certain new and useful improvements in vanity cases and 10 more particularly pertains to a vanity case for use with loose powder.

The primary object of the invention is to provide improved means for retaining the powder in position in the case, which means 15 permits the powder to readily engage the puff, and which also maintains engagement with the surface of the powder regardless of the quantity or depth thereof so as to hold the powder in position.

20 A further object of the invention is to provide powder holding means which directs the powder toward the center of the case where same can more readily be caused to engage the puff.

25 The invention still further aims to provide means of the character mentioned, which is of simple, compact and economical construction and which is embodied in an unitary structure devoid of moving parts.

30 In the drawings:—

Figure 1 is a plan view of a vanity case constructed in accordance with the present invention, and

35 Figure 2 is a central longitudinal sectional view, with the case in closed position.

In proceeding in accordance with the present invention, a case of any desired form or shape is employed, having a body 1 and a top 2 hinged at 3 and provided 40 with the customary latch 4.

A screen, mesh or other foraminous member 5 has a marginal metal binding edge or clip 6 affixed thereto.

The clip which conforms in configuration 45 to that of the margin of the screen is of substantially S-shape in cross section and has its upper loop 7 clamped about the marginal edge of the screen, while its lower loop 8 is clamped about the inner marginal edge of a ring like flexible member 9 preferably of felt. The member 9 may be of tapered cross-section, with its widest portion at its periphery, and has the latter formed to snugly engage or fit against a 50 ring-like side wall 10 secured in the body and

conforming in outline to that of the periphery of the felt member 9. The cover 2 preferably fits within the wall 10.

The screen, it will thus be seen seats on the surface of the powder and as such surface through use approaches the bottom of the body, the screen automatically follows same. The screen and the felt member are thus supported by the powder and the felt member has snug frictional contact at its 65 periphery with the wall 10 and prevents the powder from moving upwardly therepast. Consequently the powder can only pass through the screen, which latter is disposed at the center of the body and accordingly directs the powder onto the center of the puff P.

The screen follower may be readily removed by engaging the same with a pin or the like to replenish the powder supply, 75 and likewise may be easily replaced, due in each instance to its frictional securement.

Having thus described my invention, what I claim as new and desire to secure by Letters Patent is:—

1. In a vanity case, a body having a side wall, a screen, a substantially S-shaped clip having its upper loop clamped about the margin of the screen, and a ring-like felt member of outwardly flared cross-section 85 clamped within the lower loop of the clip and having its peripheral edge frictionally engaged with the side wall of the body.

2. In a vanity case, a body having a side wall, a screen, a felt member seating on the 90 surface of the powder and secured to and extending outwardly beyond the periphery of the screen and having its periphery frictionally and movably engaged with the side wall of the body, and means to connect 95 the felt member to the screen.

3. In combination with a vanity case having a body formed to contain powder, a foraminous follower, and a flexible imperforated member carried by the follower 100 and extending outwardly from the periphery thereof, and frictionally and movably engaged with the body and formed to seat on the surface of the powder.

4. In combination with a vanity case having a body formed to contain powder, a foraminous follower, and a textile imperforate member carried by the follower and extending outwardly from the periphery thereof and frictionally and movably en- 110

gaged with the side wall of the body and formed to seat on the surface of the powder.

5. In combination with a body formed to contain powder, a foraminous follower, and a flexible imperforate member carried by the follower and extending outwardly from the periphery thereof, said member having frictional and sliding engagement with the

body and having an inclined under face which tapers upwardly from the point of contact with the body toward the follower and which seats on the surface of the powder.

In testimony whereof I have signed my name to this specification.

THEODORE W. FOSTER.
